MOTORCYCLE CHAIN STORAGE COMPARTMENT

Bennett L. Heck, 2316 N. Neva, Chicago Ill. 60635, and Kenneth W. Raczyński, 2925 N. Normandy, Chicago, Ill. 60634

Filed Sept. 3, 1974, Ser. No. 502,779

Term of patent 14 years

Int. Cl. D12—11

U.S. Cl. D12—158

FIG. 1 is a front elevational view of a motorcycle chain storage compartment showing our new design it being understood that the broken lines are for illustrative purposes only;

FIG. 2 is a perspective view thereof to an enlarged scale;

FIG. 3 is a right side elevational view thereof to an enlarged scale;

FIG. 4 is a front elevational view thereof to an enlarged scale;

FIG. 5 is a top plan view thereof to an enlarged scale;

FIG. 6 is a left side elevational view thereof to an enlarged scale; and

FIG. 7 is a bottom plan view thereof to an enlarged scale.

The undisclosed rear of the motorcycle chain storage compartment is substantially flat and unornamented.

We claim:

The ornamental design for a motorcycle chain storage compartment, as shown and described.
